Application filed July 19, 1898. Serial No. 686,372. Term of patent 14 years.

To all whom it may concern:

Be it known that I, ALFRED BRUNOT SCHANZ, a citizen of the United States, residing at Attica, in the county of Fountain and State of Indiana, have invented and produced a new and original Design for Display-Stands, of which the following is a specification, reference being had to the accompanying drawings, forming a part thereof.

15 As shown in the drawings, the leading or material feature of my design consists of a triangular-shaped body portion A, having con-

nected therewith at its back a support A² and a latch A³, the support and latch being shown in Fig. 2.

Having thus described my invention, what I claim, and desire to secure by Letters Patent, is—

The design for a display-stand, as herein shown and described.

In witness whereof I have hereunto set my hand in the presence of two witnesses.
